UNITED STATES PATENT OFFICE.

JAMES H. PERRIN, OF COLUMBUS, OHIO, ASSIGNOR OF ONE-HALF TO
COLONEL E. BRIGHT, OF COLUMBUS, OHIO.

PRESS FOR MOLDING BUILDING-BLOCKS.

SPECIFICATION forming part of Letters Patent No. 752,298, dated February 16, 1904.

Application filed September 24, 1903. Serial No. 174,477. (No model.)

To all whom it may concern:

Be it known that I, JAMES H. PERRIN, a citizen of the United States, residing at Columbus, in the county of Franklin and State of Ohio, have invented a new and useful Improvement in Presses for Molding Building-Blocks, of which the following is a specification.

This invention relates to presses for molding blocks which are to be used in the construction of buildings; and it has for its objects the production of a press for that purpose which is simple and strong in construction and which is convenient and rapid in operation. These objects I attain in the structure shown in the accompanying drawings, in which—

Figure 1 is a perspective view of my press, one of the side pieces of the mold being broken away in part in order that the interior of the mold may be more clearly seen. Fig. 2 is a bottom plan view of the side pieces of the mold and of the various levers for operating the same. Fig. 3 is a transverse section through the mold with the levers shown in Fig. 2 omitted and showing the system of levers for lifting the bottom frame. Fig. 4 is a sectional view on the line 4-4 of Fig. 3. Figs. 5 and 6 are plan and central longitudinal sectional views, respectively, of the bottom frame of the mold; and Fig. 7 is a detail view.

Similar reference characters designate corresponding parts throughout the several views of the drawings, in which—

35 1 represents the main frame, which is supported upon any suitable kind of legs or supports 100, so as to bring the press to a proper height for convenient operation. The size and form of the main frame 1 will be varied 40 with the sizes and forms of the blocks which it is desired to mold on the press.

2 represents the side pieces of the mold, and 3 represents the end pieces thereof. These pieces stand in vertical positions, so that when 45 they are brought together, as shown in Fig. 1, they will form a closed rectangular mold. The pieces are held in vertical positions by means of the dovetailed, right-angled exten-

sions 4, which extensions are mounted in dovetailed ways in the upper surface of the main frame, so that they can slide back and forth therein. The extensions 4 are moved back and forth with the pieces 2 and 3 of the mold by means of a lever 5, that is pivoted at 6 substantially below the center of the mold and that projects a sufficient distance beyond the press to give the necessary leverage. Jointedly connected with the lever 5 at points 7 and 8 equidistant from the pivot 6 are two levers 9 and 10, that extend in opposite directions from the lever 5, and they are moved endwise when the lever 5 is rocked upon its pivot. The outer ends of these links are connected to shorter links 11 and 12, said shorter links being attached to the end pieces of the mold. The links 9 and 10 are also connected at 13 and 14 to the ends of toggle-levers 15 and 16, respectively, said toggle-levers being attached at their outer ends to the side pieces 2 of the mold, the points of attachment of these toggle-levers being near the ends of said pieces and being at the lower ends of extensions 160 on said side pieces, said extensions appearing clearly in Fig. 1 of the drawings. From this description it will be seen that 75 when the lever 5 is rocked in the direction of the arrow in Fig. 2 the links 9 and 10 will move outwardly, which movement will result in separating the side and end pieces of the mold.

80 For securing lightness and economy it is desired to make the building-blocks hollow, and for this purpose I place within the mold the two core-pieces 17, said pieces being so located as to leave a continuous space about 85 and between them within the mold. Of course where extreme strength is essential these cores could be made small or could be omitted altogether. As shown, they are gradually tapered toward their upper surfaces, so 90 that they will permit the molded block to be raised without damage thereto.

The bottom part of the mold is occupied by a lifting-frame 18, (shown in detail in Figs. 5 and 6,) said frame fitting closely about the 95 cores 17 and also fitting within the side and

end pieces of the mold when the latter are moved to their closed positions, as is shown in Fig. 3.

The building-block is formed of concrete or other suitable material, which is introduced into the mold in a plastic condition, the said material completely filling the mold round about the cores 17. After molding it is necessary to set the blocks aside, so that they may harden or set. In order to take the blocks from the mold, I provide means for lifting bodily and in a horizontal plane the lifting-frame 18, said means being shown in Fig. 3 of the drawings and consisting of levers 19, that are pivoted near their centers to depending brackets 30 on the lower side of the main frame 1, said levers having pivoted to their outer ends the lifting bars or rods 21. These bars or rods 21, a detailed view of which is shown in Fig. 7, are provided on their upper ends with extended head-pieces 22, upon which the outer ends of the lifting-frame 18 rest. To the inner ends of the levers 19 is connected, by means of pin-and-slot connections, a link 23, which is adapted to be moved up and down by any suitable mechanism. When moved downwardly from the position shown in Fig. 3, the outer ends of the levers 19 are elevated, with the result that the frame 18 and the block that has been molded thereon are lifted upwardly, so that the frame and block may be removed from the press to a convenient point where the block can harden. In order that the lifting-board, with the block thereon, may be conveniently lifted from the floor or shelf where it may be deposited, I place cleats 24 on the lower side of the lifting-frame, said cleats being of such thickness that workmen can easily insert their fingers under the frame.

The operation of the press is as follows: With the parts in the position shown in Fig. 3 the mold is filled with the material from which the block is formed. When a sufficient quantity of the material has been introduced, the lever 5 is rocked, so as to move the side and end pieces of the mold apart, which movement will permit the block to be lifted without damage to its exterior surfaces. The rod 23 is then depressed, which operation results in lifting the frame 18, with the block thereon, out of the mold, so that they may be removed.

The structure thus described enables me to form the building-blocks in a rapid and convenient manner, and the blocks when thus pro-

duced are square on their outer faces, so that they will form a perfectly plumb wall when erected one on another.

Having thus described my invention, what I claim as new, and desire to secure by Letters Patent, is—

1. In a device for molding blocks, a main frame, slideways formed in said frame, laterally-movable pieces guided in said slideways, said pieces forming a mold for the blocks, a main lever pivoted to said frame, links jointedly connected to said lever on opposite sides of its pivotal point, connections between said links and the end pieces of the mold, and toggle-levers connecting the said links with the side pieces of the mold, whereby when the main lever is operated the side and end pieces will be separated from each other, for the purpose specified. 75

2. In a device for molding blocks, a main frame, slideways formed in said frame, laterally-movable pieces guided in said slideways, said pieces forming a mold for the blocks, a main lever pivoted to said frame, links jointedly connected to said lever on opposite sides of its pivotal point, connections between said links and the end pieces of the mold, toggle-levers connecting the said links with the side pieces of the mold, a lifting-frame in the bottom of the mold upon which the blocks are formed, and means for lifting said frame so that it and the block thereon may be removed from the mold. 85

3. In a device for molding blocks, a main frame, slideways formed in said frame, laterally-movable pieces guided in said slideways, said pieces forming a mold for the blocks, a main lever pivoted to said frame, links jointedly connected to said lever on opposite sides of its pivotal point, connections between said links and the end pieces of the mold, toggle-levers connecting the said links with the side pieces of the mold, a lifting-frame within the mold upon which the blocks are formed, levers pivoted on the main frame beneath the mold, lifting-bars pivoted to said levers and projecting below the said lifting-frame, and a movable link connecting the said pivoted levers. 100 105

In testimony whereof I affix my signature in the presence of two witnesses.

JAMES H. PERRIN.
